Leonard W. Johnson, Batavia, Ill.; Helena E. Johnson, executrix of said Leonard W. Johnson, deceased, assignor to Helena E. Johnson

Application March 15, 1941, Serial No. 383,486

7 Claims. (Cl. 81—53)

My invention relates to torque wrenches and has particular reference to a torque wrench of the slip joint variety, in which a friction member mounted in a lever is held in engagement with a work engaging member, preferably in the form of a circular boss, and in which the friction member slips or moves away from its seat in the recess provided for the reception of the friction member in the work engaging member upon a predetermined force being applied to a nut.

This application is a continuation in part of my application Serial No. 255,405, filed February 9, 1939, this present application disclosing a combined stop and a thrust pad in addition to the elements mentioned above which I have found both desirable and necessary to the proper operation of the wrench.

Another and further object of my invention is the provision of a torque wrench provided with a stop which prevents the turning of the lever portion of the wrench a great distance after the breaking or slippage of the joint has occurred, thereby adding to the speed and ease of operation of the wrench and also preventing the lever portion of the wrench from turning such a distance that a workman is liable to injury from slipping due to the sudden release of the friction member.

Another and further object of my invention is the provision of a torque wrench having a stop member therein which permits pulling nuts tighter when the slots in castellated nuts do not line up with holes in the bolts for cotter keys after the nuts have been pulled to a predetermined pressure. This is particularly advantageous in the setting of bolts on the connecting rods of internal combustion motors.

A further object of my invention is the provision of a wrench having a thrust pad embodied therein, which acts on the boss to produce friction and adds to the accuracy of the wrench, in that it absorbs to a certain degree the force exerted upon the lever portion of the wrench when given a shock pull as distinguished from a slow, steady pull.

No two workmen pull a wrench in exactly the same manner, although to achieve the best results with a slip joint torque wrench, a slow, steady pull, gradually increasing in force until the joint breaks, is most desirable. However, at the speed of operation with which these wrenches are employed, in the final setting of the nut a workman frequently will give the wrench a quick, hard pull, with the muscles of his arm tensed, producing what is in the nature of a shock pull, in which case the nut is pulled

more tightly on the bolt than what is secured with the slow, steady pull. For this reason I prefer to add the thrust member to produce friction in the boss, which tends to lessen the effects of the shock pull and increases the accuracy of the wrench whether a pull is slow and steady, or whether a fast pull is resorted to or whether the lever is pulled with what is described above as a shock pull.

A further object of my invention is the provision of a thrust member opposite the line of force exerted by the friction member forming the slip joint, whereby the tendency of the wrench to cant during the pulling thereof is prevented, thereby preventing a binding of some of the moving parts of the wrench and resulting in increased accuracy of the wrench.

These and other objects of my invention will be more fully and better understood by reference to the accompanying sheets of drawings, and in which—

Figure 1 is a longitudinal sectional view of my improved wrench, taken on a line through the center of Figure 2;

Figure 2 is a longitudinal view of my improved wrench, partially in section and partially in elevation, taken on a vertical line through Figure 1;

Figure 3 is a view partially in elevation and partially in section, of a plan of a wrench embodying my invention;

Figure 4 is a vertical view, partially in section and partially in elevation, of the wrench shown in Figure 3; and

Figure 5 is a cross-sectional view taken on line 5—5 of Figure 3.

Referring now specifically to the drawings, and in which like reference characters refer to like parts throughout, a lever 10 is shown, having a head portion 11 having a circular opening therein, within which a circular boss 12 or work engaging member is positioned. The boss 12 has trunnions 13 and 14 on each side thereof, with their axes parallel with the axis of the boss 12, the trunnion 14 being extended to form a squared end portion 15 adapted to engage the usual socket employed with wrenches of this type for the purpose of fitting the wrench to nuts of varying thicknesses and contours. The lever 10 is made up of the head portion 11 having a hollow trunnion 16 at one side thereof, a hollow extension 17 fitted inside of the trunnion 16 and secured thereto by means of rivets 18, 18, and a handle 19. A socket is formed in the handle 19 into which one end of the extension 17 is fitted, the handle portion being held to the member 17 by

means of a screw 28. The handle 19 has a web 21 located therein, the rear end of the handle 19 being hollow, with a member 22 threaded through the web 21 being provided having a squared socket 23 in the rear end thereof into which a wrench or other tool can be fitted for turning the threaded member 22.

The boss 12 has a triangular-shaped recess 24 in one side thereof, normally in alignment with the axis of the trunnion 16, the recess having a wall 25 at one side thereof which presents substantially a vertical face in alignment with the longitudinal axis of the lever 10, while the opposite side has an angular surface 26 at approximately 30° to a vertical plane through the boss 12. A friction or latch member 27, circular in cross-section, is fitted into the bore in the trunnion 16, with its forward end angularly formed in normal position to fit against the vertical wall 25 and the angular wall 26 in the boss 12. A spring 28 is mounted in the trunnion 16 and extension 17, with a follower 29 at the rear end thereof against which the threaded member 22 abuts, so that the spring 28 can be placed under compression, as may be desired, by turning the threaded member 22 with a wrench or other appropriate tool placed in the socket at its rear end, thereby increasing or diminishing the force of the frictional engagement of the friction member 27 and the boss 12. An indicator 30 is secured to the follower 29 at one of its ends, and projects out through a slotted opening in the extension 17 alongside of a gauge plate 31, usually calibrated in foot pounds to indicate to the user the proper tension which can be applied to a nut when the wrench is in use.

A recess 32 is provided in the outer periphery of the boss 12, within which a pin 34 is fitted, the outer end of which is threaded at 35 so as to hold the pin in position in the head 11. This pin 34 limits the radial movement of the head portion 11 around the circular boss 12 when the joint between the friction member 27 and the boss 12 breaks or slips in the operation of the wrench, thereby preventing a workman from injuring himself, and limiting the distance which the lever travels when the joint breaks or slips so the wrench can be quickly returned to operative position.

A thrust member 36 is slidably mounted in an opening 37 provided through the circular head portion 11, with a threaded screw 38 in engagement with the internally threaded opening 37. The inner end of the thrust member 36 is concave and of the same curvature as the outer periphery of the boss 12, so that friction can be applied to the surface of this boss 12 to overcome the effects of a shock pull, such as hereinabove described, and because of its location on the opposite side of the boss from the friction member 27 when fitted tightly against the boss 12, also removes or minimizes the friction at the sides of the trunnions 13 and 14 on their sides opposite the friction member 27. The head portion 11 of the lever at one side thereof has an opening 39 formed therein, while at the opposite side of the head a plate 40 is provided having an opening 41 therein fitting around the trunnion 14. The force of the thrust of the spring 28 as exerted through the friction member 27 and the boss 12, would be borne by the trunnions 13 and 14 if the thrust member 36 were not present. Through the proper thrust applied to the boss 12, this friction is balanced. Also during the

pulling operation upon the handle of the wrench against the resistance given by the nut, there is a tendency for the head 11 to cant or bind at the sides of the trunnions, and this is overcome by placing the thrust member 36 exactly opposite the bearing point of the friction member 27, so that in effect the entire force of the pull is exerted in a radial direction upon the nut, thereby increasing the accuracy of the wrench in addition to preventing a wide variation in the use of the wrench due to the shock pull.

Referring now specifically to Figures 3 to 5, inclusive, which are the same as Figures 11 to 13 of my application Serial No. 255,405, a lever is shown having a head portion 42, with a hollow extension 43 in threaded engagement with a trunnion 44 forming an extension of the head portion 42. A circular boss 45 is provided having a plurality of arcuate-shaped recesses 46, 46 in the periphery thereof, and in addition having recesses 47, 47 within which a stop and friction member 48 is adapted to be seated. A spring 49 and threaded member 50 are provided, being mounted in the circular head 42 through an opening formed therein, in such manner that the member 48 forms a stop against complete rotation of the lever around the boss 45. At the same time it exerts sufficient friction against the side of this member to prevent quick movement of the parts due to a shock pull in the use of the wrench.

The boss 45 has a trunnion 54 at one side thereof and a trunnion 52 at the opposite side, with a squared extension 53 extending outward from the trunnion 52 forming a workpiece. A bolt 54 is fitted to the opposite side of the wrench, and a threaded ring 55 is provided in threaded engagement with the head 42, thereby holding the boss 45 in position in the head 42.

A follower 56 is provided, having a pair of spaced arms 57 and 58 thereon, between which is mounted a roller 59 on a pin 60, the periphery of the roller being of the same contour as the arcuate-shaped recesses 46 and adapted to be fitted thereon during the normal operation of the wrench. A spring 61 is provided having a follower 62 mounted in the extension 43, with the same adjusting mechanism on the rear of the wrench as is shown in Figures 1 and 2, to secure the proper tension on the spring 61. In addition to the tension imparted to the follower 62, a friction member 63 is provided seated in a recess in the wall of the member 43, with a threaded member 64 abutting against the outer side thereof, this member being shown particularly in Figure 5. The inner face of the member 64 is arcuate and of the same curvature as the follower 56, so that pressure upon the screw 64 as it is screwed tightly into position, exerted against the follower, increases the friction on the follower 56 and more force is required to move the handle with reference to the boss than if this member were not employed.

In operation of the device, it will be understood that when it is desired to turn a nut to the proper tension, the spring is adjusted in either instance by means of the threaded member 22 and a socket applied to the squared ends either 45 or 53, and the wrench applied to the nut in the usual manner. The force sufficient to turn the nut until the friction member slips or moves partially out of the recess provided in the outer periphery of the boss, indicates to the workman that the nut has been turned up to the desired degree of tightness. As the workman exerts a force upon the

handle and after the critical point is reached in the use of the wrench, the lever portion slips on the boss, and the friction member rides up toward the side of the boss a short distance, where further rotative movement is prevented by the stop 34, in the wrench shown in Figures 1 and 2, and by the stop 48 in Figures 3 and 4. The thrust member 36 is set to maintain a pressure or friction on the boss, and as the workman turns a nut up almost to the point of setting, he is apt to exert a quick, hard, tense pull on the wrench, finally setting the nut under the required tension. When such a pull is exerted, the force is absorbed to a limited extent by the resistance to movement between the thrust member and the boss, just at the instant when the joint breaks, which results in a more accurate setting of the nut than if the thrust member were not employed. This movement is somewhat limited but it is sufficient to indicate to the workman that the desired tension has been reached, and thereafter it is very easy to turn the wrench back to operating position ready to be used upon the next or succeeding nut, or to back up the nut slightly for use with a castellated nut, or the nut may be turned more tightly to bring the pin receiving channels in the nut into register with the hole in the bolt through which the usual cotter pin is inserted. In this manner there is no danger of the handle turning around too far, or, as often happens, of the wrench releasing very quickly allowing the workman to strike his hand against some adjoining pieces of machinery, thereby resulting in injury to him.

In addition, as shown in Figures 1 and 2, the friction member produces in effect a balanced friction or at least reduces it to a point somewhat small in area, and enables the wrench to be pulled in a straight direction without a tendency to cant or tip over, producing, in effect, a floating action of the wrench. In this way I have found that a material degree of safety and also an added amount of accuracy is provided in a torque wrench, which is not possible to secure with other types of torque wrenches now in use.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

What is claimed is:

1. A slip joint wrench comprising in combination, a lever having a handle portion and a head portion, a circular work engaging boss mounted in said head portion having a latch receiving recess and a stop receiving recess wider than the stop to be received therein in its outer periphery, a latch in the handle portion forming a slip joint between the lever and the work engaging boss, a stop on said head portion extending into the said stop receiving recess, a spring in said handle in engagement with one end of the said latch member, adjustable abutting means for said spring mounted in said handle, and a combined friction producing and thrust member in said head portion in engagement with the said work engaging boss.

2. A slip joint wrench comprising in combination, a lever having a handle portion and a head portion, a work engaging boss mounted in the said head portion having latch receiving and stop receiving recesses therein, a latch member, one

end of which seats in the latch receiving recess, a spring in the handle, adjusting means whereby varying pressures are exerted on said spring, a stop in the head portion of the lever extending into the stop receiving recess in the said boss, the stop receiving recess being wider than the stop therein whereby limited rotative movement of the lever and work engaging boss is obtained, and a combined friction producing and thrust member in said head portion in engagement with the said work engaging boss.

3. A slip joint wrench comprising in combination, a lever having a handle portion and a head portion, a work engaging boss mounted in the said head portion having latch receiving and stop receiving recesses therein, a latch member, one end of which engages the latch receiving recess, a spring in the handle, adjusting means whereby varying pressures are exerted on said spring, and a stop in the head portion of the lever extending into the stop receiving recess in the said boss, the stop receiving recess being wider than the stop therein whereby limited rotative movement of the lever and work engaging boss is obtained and of a width sufficiently narrow whereby the latch member is partially retained in the latch receiving recess at all times.

4. A torque wrench comprising in combination, a lever having a head portion at one of its ends, a cylindrically shaped work engaging member in said head portion and normally movable relative thereto, said work engaging member having at least one pair of recesses in the periphery thereof, one of said recesses being fashioned to receive a latch member and the other recess to receive a stop member, a latch member in said handle, a spring mounted in the lever in abutting engagement with the rear end of said latch member, an adjustable follower in the said lever forming an abutting support for the said spring, and a stop in said head portion extending into the recess in the work engaging member, the said stop receiving recess being sufficiently wider than the stop to permit limited relative movement of the work engaging boss and the lever to an extent insufficient to allow a complete disengagement of said latch member from said latch receiving recess.

5. A torque wrench comprising in combination, a lever having a head portion at one of its ends, a work engaging member in said head portion and normally movable relative thereto, said work engaging member having at least one pair of recesses in the periphery thereof, one of said recesses being fashioned to receive a latch member and the other recess to receive a stop member, the outer surface of the work engaging member being circular, a latch member in said handle, a spring mounted in the lever in abutting engagement with the rear end of said latch member, an adjustable follower in the said lever forming an abutting support for the said spring, a stop in said head portion extending into the recess in the work engaging member, the said stop recess being sufficiently wider than the stop to permit limited relative movement of the lever and work engaging boss, and a combined thrust and friction member in said head portion in normal engagement with the surface of the said work engaging member.

6. A torque wrench comprising in combination, a lever having a head portion at one of its ends, a work engaging member in said head portion and normally movable relative thereto, said work engaging member having a pair of recesses

in the periphery thereof, one of said recesses being fashioned to receive a latch member and the other recess to receive a stop member, the outer surface of the work engaging member being circular, a latch member in said handle, a spring mounted in the lever in abutting engagement with the rear end of said latch member, an adjustable follower in the said lever forming an abutting support for the said spring, a stop in said head portion extending into the recess in the work engaging member, the said stop receiving recess being sufficiently wider than the stop to permit limited movement of the work engaging boss, and a combined thrust and friction member in said head portion in normal engagement with the surface of the said work engaging member, the inner face of the friction member being concave to conform to the surface of the work engaging member.

5. A torque wrench comprising in combination, a lever having a head portion at one of its ends, a cylindrically shaped work engaging member in said head portion and normally movable relative thereto, said work engaging member having a latch receiving recess in the periphery thereof, a latch member in said handle, a spring mounted in the lever and in abutting engagement with the rear end of said latch member, an adjustable follower in the said lever forming an abutting support for the said spring, and cooperating means on said cylindrically shaped work engaging member and said head portion whereby the relative movement of one of these parts with respect to the other is limited to an extent which prevents a disengagement of said latch member from said latch receiving recess.

10. A torque wrench comprising in combination, a lever having a head portion at one of its ends, a cylindrically shaped work engaging member in said head portion and normally movable relative thereto, said work engaging member having a latch receiving recess in the periphery thereof, a latch member in said handle, a spring mounted in the lever and in abutting engagement with the rear end of said latch member, an adjustable follower in the said lever forming an abutting support for the said spring, and cooperating means on said cylindrically shaped work engaging member and said head portion whereby the relative movement of one of these parts with respect to the other is limited to an extent which prevents a disengagement of said latch member from said latch receiving recess.

15. A torque wrench comprising in combination, a lever having a head portion at one of its ends, a cylindrically shaped work engaging member in said head portion and normally movable relative thereto, said work engaging member having a latch receiving recess in the periphery thereof, a latch member in said handle, a spring mounted in the lever and in abutting engagement with the rear end of said latch member, an adjustable follower in the said lever forming an abutting support for the said spring, and cooperating means on said cylindrically shaped work engaging member and said head portion whereby the relative movement of one of these parts with respect to the other is limited to an extent which prevents a disengagement of said latch member from said latch receiving recess.

7. A torque wrench comprising in combination, a lever having a head portion at one of its ends, a cylindrically shaped work engaging member in said head portion and normally movable relative thereto, said work engaging member having a latch receiving recess in the periphery thereof, a latch member in said handle, a spring mounted in the lever and in abutting engagement with the rear end of said latch member, an adjustable follower in the said lever forming an abutting support for the said spring, and cooperating means on said cylindrically shaped work engaging member and said head portion whereby the relative movement of one of these parts with respect to the other is limited to an extent which prevents a disengagement of said latch member from said latch receiving recess.

LEONARD W. JOHNSON.
